UNITED STATES PATENT OFFICE.

PETER M. WEGE, OF MARIETTA, OHIO, ASSIGNOR TO THE SAFE CABINET COMPANY,
OF MARIETTA, OHIO, A CORPORATION OF OHIO.

COMBINED SHELF AND PARTITION.

1,038,038.

Specification of Letters Patent. Patented Sept. 10, 1912.

Application filed May 17, 1911. Serial No. 627,658.

To all whom it may concern:

Be it known that I, PETER M. WEGE, a citizen of the United States, residing at Marietta, in the county of Washington and 5 State of Ohio, have invented a certain new and useful Improvement in Combined Shelves and Partitions, of which the following is a specification.

The object of this invention is to provide 10 a combined shelf and partition more especially for sheet metal cabinets, cases and the like, it being my particular aim to make these of simple and economical construction and so that the partition while readily 15 moved or adjusted by proper manipulation shall be comparatively rigid and not liable to have its position disturbed in the ordinary use of the cabinet.

The invention is embodied in the construction herein shown and set forth and then particularly pointed out in the claim.

In the accompanying drawing Figure 1 is a front view of a cabinet of the kind in which such a shelf and partition may be 20 employed said view illustrating the cabinet broken out horizontally at the middle and with the upper portions of the doors removed. In this view the edges of two partitions and a shelf in the upper portion of 25 the cabinet are also shown as broken out. Fig. 2 is a perspective view on a larger scale of fractions of a shelf and partition to illustrate the details of the construction. Fig. 3 is a vertical section also on a larger 30 scale than that of Fig. 1 to further illustrate details of construction.

In the views 5 designates the body of the shelf which is of sheet metal. At its front edge the margin of the shelf is bent downwardly and inwardly to form a right angled groove 6. At its rear edge the margin is first bent and folded upon itself to form a tongue 7 and then downwardly and inwardly to form a right angled groove 8. 45 The body of the partition which is also of sheet metal is designated 9. The upper edge

of the metal forming the partition is bent first horizontally as seen at 10 then vertically as seen at 10^a and then backward horizontally as seen at 10^b so as to form a thick 50 hollow tongue standing at one side of the vertical plane of the partition. The metal of the partition is sawed out or cut away horizontally just under the two ends of this tongue as seen at 11 and 12 so that said 55 ends can be inserted in the rectangular grooves 6 and 8 as best shown in Fig. 3. The said tongue of the partition is made to snugly fit in the grooves 6 and 8 and so that the walls 10 and 10^b bear with a spring 60 pressure against the corresponding walls of the groove. This spring pressure serves to keep the partition at the place to which it is adjusted until the partition is manipulated with an intelligent pressure applied 65 near to the tongue to move it to the right or left.

The shelf can be supported in the walls of the cabinet by any suitable manner as for example in horizontally extending grooves 70 such as shown at 13 made in the end and rear walls.

I do not confine myself to the exact proportions of the parts herein shown or described as they can be modified without departing from the gist of the invention. 75

What I claim is:

In a cabinet of the kind indicated, the combination with a sheet metal shelf formed at its lower side with grooves at its front 80 and rear edges, of a partition of sheet metal having at its upper edge a hollow tongue including substantially horizontal walls and a wall connecting them one of said walls being free to be sprung toward the other, 85 said tongue projecting at its ends to enter and engage the aforesaid grooves.

PETER M. WEGE.
